UNITED STATES PATENT OFFICE.

HERBERT D. STELLE AND WILLIAM E. BAXTER, OF LOS ANGELES, CALIFORNIA.

COMPRESSION AXLE-LUBRICATOR.

1,011,136.

Specification of Letters Patent

Patented Dec. 5, 1911.

Application filed November 19, 1910. Serial No. 593,246.

To all whom it may concern:

Be it known that we, HERBERT D. STELLE and WILLIAM E. BAXTER, both citizens of the United States, residing at Los Angeles, in the county of Los Angeles and State of California, have invented a new and useful Compression Axle-Lubricator, of which the following is a specification.

An object of this invention is to provide

10 a lubricating device by which the bearing between an axle and a wagon wheel or the like can be lubricated in a superior manner and without leakage of the lubricant or permeation of the wooden hub or axle by the lubricant.

15 A further object is to so construct the lubricator as to thereby fix the wooden hub to the metal box of the wheel and to hold the hub in fixed relation to the metal parts 20 connected therewith without danger of the hub becoming loose.

The accompanying drawings illustrate the invention in the form at present deemed most desirable.

25 Figure 1 is a perspective view of the newly invented lubricator as applied in a wagon wheel and axle, a fragment only of the wheel being shown. Parts are broken to expose interior construction. Fig. 2 is 30 a plan section practically on line x^2-x^2 , Fig. 1. Fig. 3 is a perspective view of the cup detached. Fig. 4 is an elevation omitting the compression head. Fig. 5 is a detail of the hub, box, cup and compression

35 head detached from each other; fragments only of the hub and box are shown. Fig. 6 is a section of another form in which the grease duct is bored through the nut.

40 The hollow wooden hub 1 is counter-bored at its outer end and inside the counter-bore near the main bore a thin practically cylindrical cleft 2 is cut, thus forming around the outer end of the main bore of the hub a short thin wooden band 3 and 45 at the outer end of the hub a thick practically cylindrical collar 4.

The metal axle-box 5 is mounted in the usual way on an axle-spindle 6 which is threaded at its outer end to receive the nut 50 6' which holds the axle-box on the spindle.

55 The combined oil-cup and hub-fastener comprises two coaxial cylinders 7, 8. The smaller one of said cylinders forms a sleeve slightly thicker than and of nearly the same radius as the cleft 2 and has a wedge-like

tip 9. Said cylinders are connected by an intermediate web 10 to fit upon the outer end of the collar 4 internally screw-threaded as at 11 to receive a screw-threaded compression head 12 which may be turned by a wrench, not shown, and screwed into the chamber 13 of the cup to reduce the space therein and to thus apply pressure to the contents thereof.

The cup may be of cast metal or may be otherwise formed and the sleeve has a slight draw; that is to say, it is reduced in thickness from the shoulder to the tip so that when driven into the recess in the hub it acts as a wedge to force the inner band 3 against the box and the outer collar 4 against the collar band 14, which encircles the end of the hub.

In practice, the wood of the hub being perfectly seasoned and dry, the cup is driven 75 into place by a hydraulic press or other means exerting a pressure of three thousand pounds, more or less; and when thus driven home it is not only effectually fixed in place by frictional contact with the walls of the 80 cleft, but it also fixes the wooden part of the hub positively to the box and also to the collar band, thus to prevent possibility of becoming loose and preventing seepage of oil around the box into the hub.

85 When the nut 6' is screwed home on the end of the axle to contact with the axle-box a solid partition or closure between the chamber of the cup and the interior of the box is thus formed and this is pierced by a thin 90 duct to form a lubricant way 15 between the grease chamber in the cup and the interior of the box 5.

In some instances, the lubricant way extends directly through the spindle from the 95 outer end thereof to a point inward beyond the screw-threaded portion as indicated at 15 in Fig. 2. In other instances, a hole 15' may be bored through the solid part of the nut from the outer to the inner face of the 100 nut to a point adjacent the shoulder 16 of the spindle, and the spindle at this point may be slightly chamfered so as to allow a free passage from the inner end of the hole to the interior of the box. By thus boring 105 the hole through the solid part of the axle or through the solid part of the nut the threaded connection between the nut and spindle is unimpaired and a very fine hole, the bore 110 of which may be as small as can be conven-

iently bored will be sufficient to admit the lubricant to the box, thus to lubricate the axle.

By boring the hole through the solid part 5 of the nut it is possible to locate the hole at such part of the nut that when the nut is screwed home the hole will be at the bottom of the axle, thus insuring the application of the lubricant to the axle with a minimum 10 amount of lubricant to the cup.

In any instance the arrangement of the lubricant way through the solid part of the partition formed by the axle and the nut between the cup and the box enables the 15 lubricant to be applied to the spindle below the top thereof.

In practice when the wheel is in place and the nut screwed home, a charge of semi-fluid lubricant, such as hard grease or 20 equivalent thereof, is put inside the lubricant cup and the compression head is then screwed in place to apply sufficient pressure to the lubricant to force a portion thereof into the box to effect the required lubrication. Said head may be screwed in slightly 25 from time to time as may be required to force the lubricant into the space inside the box.

We claim:—

30 The combination with a metal axle-box, a spindle in the box and a nut on the end

of the spindle to retain the box on the spindle; of a hub mounted on the box and provided at one end with a thin hollow practically cylindrical band around the box and 35 a thick hollow cylindrical collar outside said band, there being a narrow annular cleft between the band and collar; a combined oil cup and hub fastener comprising two hollow coaxial cylinders of different diameters, 40 connected by an intermediate web, the outer cylinder being internally screw-threaded and the inner cylinder being tightly wedged into the cleft, and at the same time wedging the band against the box to fix the hub on the 45 box and being fixed to the hub by frictional contact with the outer and inner walls of the cleft; and a screw-threaded compression head screwed into the threaded cylinder, thus forming a closed chamber containing 50 said nut; there being an oil way between the interior of the threaded cylinder and the interior of the box.

In testimony whereof, we have hereunto set our hands at Los Angeles, California, 55 this 11th day of November, 1910.

HERBERT D. STELLE.
WILLIAM E. BAXTER.
